(57) **CLAIM**

The ornamental design for a sheet-formed container for frangible items, as shown and described.

DESCRIPTION

FIG. 1 is an isometric view of a sheet-formed container for frangible items in accordance with the present design;
FIG. 2 is a top plan view of the sheet-formed container for frangible items of FIG. 1;
FIG. 3 is a bottom plan view of the sheet-formed container for frangible items of FIG. 1;
FIG. 4 is a front view of the sheet-formed container for frangible items of FIG. 1;
FIG. 5 is a rear view of the sheet-formed container for frangible items of FIG. 1;

FIG. 6 is a right-side view of the sheet-formed container for frangible items of FIG. 1;
FIG. 7 is a left-side view of the sheet-formed container for frangible items of FIG. 1;

FIG. 8 is a cross-section view taken along cross-section lines VIII-VIII of the sheet-formed container for frangible items of FIG. 1; and,

FIG. 9 is a cross-section view taken along cross-section lines IX-IX of the sheet-formed container for frangible items of FIG. 1.

The broken line showing of a container is included for the purpose of illustrating environmental structure only and forms no part of the claimed design.
